DESIGN FOR AN ATOMIZER

Meyer Milton Katz, Philadelphia, Pa.

Application January 20, 1947, Serial No. 136,253

Term of patent 7 years

(Cl. D83—1)

To all whom it may concern:

Be it known, that I, Meyer Milton Katz, a citizen of the United States, residing in Philadelphia, Philadelphia County, Pennsylvania, have invented a new, original, and ornamental Design for an Atomizer, of which the following is a specification, reference being had to the accompanying drawings, forming a part thereof.

Fig. 1 is a side elevational view of an atomizer showing my new design;

Fig. 2 is a front elevational view of the atomizer;

Fig. 3 is a rear elevational view of the atomizer;

Fig. 4 is a top plan view, and

Fig. 5 is a plan view of the bottom of the atomizer.

I claim:

The ornamental design for an atomizer, as shown.

MEYER MILTON KATZ.
